UNITED STATES PATENT OFFICE.

JULIUS C. RIETH, OF SANDWICH, ILLINOIS.

PNEUMATIC GRAIN-ELEVATOR.

SPECIFICATION forming part of Letters Patent No. 717,926, dated January 6, 1903.

Application filed August 5, 1902. Serial No. 118,478. (No model.)

To all whom it may concern:

Be it known that I, JULIUS C. RIETH, a citizen of the United States, residing at Sandwich, in the county of Dekalb and State of Illinois, 5 have invented certain new and useful Improvements in Pneumatic Grain-Elevators; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to pneumatic elevators, and it relates particularly to means for conveying grain or other light substances to points of shipment or storage.

The object of the invention is to provide 20 means for elevating or conveying grain or other light substances from one place to another in such manner that the current of air by which the grain or other substances is conveyed shall not be interrupted or its force 25 weakened by reason of escape or deflection in its passage through the device.

With this object in view the invention consists of a device for conveying or elevating grain or other light substances which consists, 30 essentially, of means for inducing a current of air, a passage into which grain or other substances are deposited, and a conduit for conveying the substance from the device, the passage being at all times closed to prevent

35 escape of air therefrom, the parts of the device being constructed and arranged substantially as hereinafter described, claimed, and illustrated in the accompanying drawings.

One form of embodiment of my invention 40 is illustrated in the accompanying drawings, in which--

Figure 1 is a perspective view of a pneumatic elevator constructed in accordance with my invention. Fig. 2 is a view similar to 45 Fig. 1, parts of the frame being broken away to show the interior disposition of the parts. Fig. 3 is a perspective view of the receiving-hopper and adjacent parts, the end being removed to show the interior of the lower portion; and Fig. 4 is a detail view showing the 50 means of connecting the shafts.

In the drawings, 1 represents the hopper of the device, into which grain or the like to be elevated or conveyed is deposited previous to being moved to the desired place of deposit 55 by the current of air employed for the purpose. In the lower portion of the hopper is a transverse passage or way 2, the same being preferably semicircular in cross-section and forming the lower portion of the passage into 60 which the grain or the like is deposited from the hopper and in which it receives the impact of the current of air by which the substance is conveyed to a pipe or conduit 3, by which it is conducted to a place of deposit. 65 The upper portion of the passage or way 2 is formed in turn by the openings between the wings 4 of the revolving cylinder 5 as the wings are brought successively to register with the upper edges of the portion of the 70 passage formed in the bottom of the hopper 1. The cylinder 5 and wings 4, which extend entirely across the hopper, form the bottom of that portion of the hopper in which the grain or the like to be elevated or conveyed 75 is deposited when entering the device, and the distance between the outer edges of adjacent wings corresponds to the width of the 80 passage 2. A circular receptacle 6 for the winged cylinder is provided in the lower end 80 of the hopper, and the outer ends of the wings fit closely against the inner face of the receptacle in order to prevent the escape of air forced through the passage 2 into the hopper 1. 85

A current of air by which the grain or the like is conveyed is generated by the fans 7 7, located in the base 8 of the device. These fans, which rotate in the direction indicated by the arrows in Fig. 2, extend entirely across 90 the base and are mounted in suitable bearings in the respective ends thereof. Each shaft 9 of the fans is provided with a gear 10, and as the gears intermesh the fans are caused to revolve in opposite directions. The base 95 8 is air-tight except at the bottom, where it is open for its entire width, allowing the inlet of air to the fans 7. Communication between the fan-chamber or base 8 and the passage 2 is established by the pipe 11, extending from 100 one to the other and located on the outside of the casing of the device.

Movement may be imparted to the various moving parts in any suitable way—as, for instance, a main driving-belt 12 is passed over a band-wheel 13 on the end of one of 5 the shafts 9, and motion given this shaft is transmitted through the gears 10 to the other shaft 9, and the cylinder 5 is driven by a belt passing over a band-wheel 14 on the second shaft 9 and over a similar band-wheel 15 on 10 the shaft of the cylinder 5.

The device thus described may be placed in any desired position for use. For instance it may be attached by means of the brackets 15 16 to a thresher, corn-sheller, or any similar machine where the grain or the like is discharged, also the loading of cars, boats, vessels, and the handling of certain grades of coal.

In the operation of the elevator or conveyer 20 motion is imparted to the parts through the main driving-belt 12, and in this way air is caused to be drawn in at the bottom of the fan-chamber and forced through the pipe 11 to the passage 2. When a strong current of 25 air is established through the passage 2 a stream of grain or the like is allowed to flow into the hopper 1. The space between each pair of arms 4 will become filled as the arms assume a position to form the lower part of 30 the hopper, and as the arms descend the charge is carried downward until the arms register with the sides of the passage 2, when it will be conveyed by the current of air, established as described, through the pipe 3 to 35 the desired place of deposit.

From the foregoing it will be clear that a device constructed in accordance with my invention is effective and economical in operation because of the fact that no interruption, 40 impeding, or escaping of the current of

air by which the substance is conveyed is possible in any part of the passage.

Having thus described my invention, what I claim as new, and desire to secure by Letters Patent, is—

1. A device of the kind described comprising a winged revoluble cylinder, a passage arranged adjacent to and parallel with the cylinder, the spaces between the outer edges of the wings corresponding to the width of 50 the passage, and the wings being adapted to register with the sides of the passage to form a closed conduit, substantially as described.

2. A device of the kind described comprising a hopper having the bottom thereof formed 55 by a revoluble winged cylinder, a passage arranged adjacent and parallel with the cylinder, the spaces between the outer edges of the wings corresponding to the width of the passage, the wings being adapted to register 60 with the sides of the passage, and means for forcing a current of air through the conduit so formed, substantially as described.

3. A device of the kind described comprising a hopper, a revoluble winged cylinder 65 forming the bottom of the hopper, a passage adjacent to the cylinder of a width corresponding to the spaces between the outer edges of the wings, means for inducing a current of air, and a pipe for conducting the air 70 to the conduit formed by the wings of the cylinder and the passage, substantially as described.

In testimony whereof I affix my signature in presence of two witnesses.

JULIUS C. RIETH.
